ALUMINUM BOAT

Application filed January 24, 1928. Serial No. 249,152.

This invention relates to a boat construction and more especially to a boat which may be constructed throughout from aluminum.

Efforts have been made heretofore to provide a light craft which could be constructed entirely of metal and which could have its parts readily assembled without expense and difficult workmanship and at the same time avoid the leakage of water through the metal-to-metal joints. Aluminum, because of its light weight and the fact that it is easily worked, adapts itself for the construction of a boat which is both rust-resisting and durable.

15 One of the primary objects of the invention is to provide an aluminum boat composed of longitudinal aluminum frame members to which aluminum body plates are securely attached against leakage, the said frame members being possessed of a degree of resiliency or yieldability to facilitate the application of the plates and the final shaping of the boat.

Another object is to provide a boat construction which may be shipped to its destination in knocked-down or disassembled formation and which may be readily assembled in an expeditious manner and without any great difficulty.

30 A further object of the invention is to provide a boat construction of aluminum embodying a keel member having lateral, longitudinal flanges to receive and firmly embrace the body plates or sheets of aluminum in a leak-proof manner.

The invention resides in the features of construction and the arrangements and combinations of parts hereinafter described and claimed, reference being made to the accompanying drawings wherein:

Fig. 1 is a cross sectional view through the improved boat.

Fig. 2 is an enlarged detailed section 45 through the keel illustrating in dotted lines the original formation of the keel before the bottom plates or sheets are attached.

Fig. 3 is a similar sectional view through one of the keelsons.

50 Fig. 4 is an elevation of the bow of the boat

depicting the keel member turned upwardly to form the bow-piece.

Fig. 5 is a cross sectional showing of a modified keel, and

Fig. 6 is a transverse section on line 6—6 of Fig. 4.

Referring more in detail to the accompanying drawing, the keel 1 and the keelsons 2 are composed of lengths of extruded aluminum each having oppositely extending, lateral pairs of flanges 3 extending substantially the entire length of the particular frame member, which flanges when originally formed diverge outwardly as indicated by the dotted showing 4 in Fig. 2, or extend substantially parallel as in Fig. 5. These flanges provide outwardly facing, longitudinal grooves 3' which facilitate the placement of the body plates. Preliminary to this, however, it is preferred to insert a quantity of water-proof cement, such as indicated at 5, following which a longitudinal edge of one of the body plates is inserted. With reference to Fig. 2, the longitudinal inner marginal portions of the bottom plates 6 are inserted in the inwardly tapering grooves of the keel 1 and the flanges are then brought into clamping relation with said interposed marginal portions, forming a

15 joint of flat, contacting, metal surfaces which may be maintained by the provision of rivets 7 which are spaced at intervals along the joints. The outer longitudinal marginal portions of the bottom plates 6 are likewise 70 clampingly and securely embraced between the inwardly extending pairs of flanges 3 of the respective keelsons 2 in a manner similar to that just described in providing the leak 75 proof joints at the keel. Each keelson is of angular section and has an upwardly extending 80 pair of flanges 3 which receive the bottom edge of the respective side plate 8, the latter constituting the sides of the boat. The upper marginal portions of the sides 8 are capped by side rails or gunwales to finish off the 85 boat and afford some rigidness thereto. The bottoms of the grooves are preferably rounded and slightly enlarged, as at 3", to freely receive the inner edges of the body plates and thereby facilitate the attachment of the latter

90 95 100

against binding distortion when bending the flanges 3 down thereonto. The groove bottoms 3" also act as cement containing chambers as shown in the enlarged views in Figs. 5 and 3, wherein the plates 6 extend partially into said chambers and are therein embedded in the cement.

The keel, as well as the keelsons, are extruded in a shape which will accord to them a degree of resiliency between their marginal pairs of flanges, whereby a certain amount of give or yieldability is provided to facilitate the attachment of the body plates and the shaping of the boat. This particular resiliency of yieldability in the frame members 1 and 2 is provided by reducing the body thickness of said frame members along their longitudinal centers, as indicated by the channels 10. This flexibility may be provided for by the attenuation of the body portion of each frame member between the marginal flanges both on the inside as well as the outside, such outside formation being indicated in Fig. 5. This construction will permit the obtaining of the desired angular relation between the body plates by reason of the giving tendency of such reduced intermediate portions of the frame members. The keel may be formed with the depending rib 1' as illustrated in Fig. 2 or this rib may be dispensed with in accordance with the slightly modified showing in Fig. 5 wherein the keel 1" is shown in process of attachment to the body plates. In constructing the bow of the boat the keel is turned upwardly at its forward end to form the bow-piece, and the forward edge portions of the bottom and side plates bowed and turned inwardly into the grooves 3' of said bow-piece and secured in the same manner as that depicted in Figs. 2 and 3, the keelsons preferably terminating in the upturned bow section of the keel as shown in Fig. 4.

As above stated, the frame members 1 and 2 are preferably extruded and then the flanges brought together to assume an outwardly divergent relation or a substantially parallel, or even an outwardly convergent relation, as is shown in Figs. 2 and 5. When the flanges are substantially parallel the body plates 6 may be inserted endwise, the marginal portions of the plates being directed by the flanges to assume the configuration of the frame members. After the body plates have been positioned between the flanges, the latter are clampingly embraced with the marginal portions of said plates by means of the rivet 7 so as to afford a tight and strong joint. The marginal portions of the keel 1 will substantially lie in the same plane at the central portion of the boat, and as the bow of the boat is reached the marginal portions will assume more or less of an acute angular relation, such as is shown in Fig. 6. The keelsons 2 will have their marginal portions angularly related through the main body portion of the

boat and will substantially flatten out to lie in substantially the same plane, as the bow is approached, in a relation of parts similar to that shown for the modified keel in Fig. 5.

A boat constructed in accordance with the present invention may be very economically manufactured, requiring only the extrusion or formation of the longitudinal frame members 1 and 2, the cutting out of the bottom and side plates, and the assembling of these parts in the manner indicated.

Prior to their assembly these constituent parts may be shipped to their destination in a very compact and knocked-down arrangement and when they are assembled a rigid leak-proof construction is afforded. By constructing the boat throughout of aluminum the joints may easily be effected and the resulting boat will possess that degree of lightness in weight which will facilitate the proper handling and manipulation of the boat in use.

What is claimed is:

1. A sheet aluminum boat comprising an aluminum keel frame member and spaced aluminum keelson frame members laterally spaced therefrom, each frame member being integral and having marginal pairs of outwardly extending flanges connected by an intermediate bendable body, an aluminum bottom plate on each side of the keel having its inner longitudinal marginal portion embraced by the flanges of the adjacent pair of said keel frame member and its outer longitudinal marginal portion embraced by the flanges of the adjacent pair of the respective keelson frame member, and side plates extending angularly from the bottom plates and embraced in the other pair of flanges of each keelson frame member.

2. A sheet aluminum boat comprising a keel frame member and spaced keelson frame members laterally spaced therefrom, each frame member being integral and having marginal pairs of outwardly extending flanges, said pairs of ears being angularly relatable upon shaping the intermediate body portion, an aluminum bottom plate on each side of the keel having its inner longitudinal marginal portion embraced by the flanges of the adjacent pair of said keel frame member and its outer longitudinal marginal portion embraced by the flanges of the adjacent pair of the respective keelson frame member, side plates extending angularly from the bottom plates and embraced in the other pair of flanges of each keelson frame member, and fastening members connecting the flanges of each pair together through the embraced marginal portions of said plates.

3. A boat comprising longitudinal keel and keelson frame members extruded from aluminum and having laterally extending pairs of flanges, the body portions of said frame members between their lateral pairs of flanges be-

ing yieldable for shaping the boat, and body plates having their longitudinal marginal portions clampingly secured between the flanges of each pair for forming the bottom and sides of the boat.

5 4. An aluminum boat comprising a keel having oppositely and outwardly facing pairs of pliable flanges, body plates having their inner margins interposed between and embraced by said flanges, said keel being turned upwardly at one end to form the bow-piece and said flanges being substantially co-extensive with said bow-piece, and said body plates at their ends being turned inwardly
15 and embraced by the flanges of said bow-piece.

5 5. A boat comprising a keel having longitudinally extending flanges on its opposite sides, the longitudinal body portion between
20 said lateral flanges being flexible to permit the springing of the flanged margin on one side of the keel into varying angular relation to the flanged margin on the opposite side, and body plates secured to said flanges.

25 6. A boat comprising a longitudinal frame member having spaced pairs of longitudinal flanges, the flanges of each pair bendable into clamping relation with an interposed body plate, body plates having margins firmly
30 embraced by said flanges, the flanges of each pair defining grooves the bottoms of which grooves being enlarged and comprising cement containing chambers to freely receive
35 said margins, and means for securing the flanges of each pair together against said margins.

7. An aluminum boat comprising a keel frame member having on its opposite longitudinal sides pairs of plate-attaching flanges
40 opening outwardly, the body portion of said frame member between said pairs of flanges being pliable to permit bending the same on the longitudinal axes of said frame member whereby one pair of flanges may be angularly
45 related relative to the companion pair of flanges in shaping the boat.

8. A boat having an aluminum keel frame member provided with spaced pairs of marginal flanges, the intermediate body portion between said pairs of flanges being reduced in thickness to render the same shapable, and a keel rib formed on the lower side of said body portion intermediate said pairs of ears.
